UNITED STATES PATENT OFFICE.

HENRY E. WEBER, OF CANTON, OHIO.

DENTAL CUSPIDOR.

SPECIFICATION forming part of Letters Patent No. 728,638, dated May 19, 1903.

Application filed September 13, 1902. Serial No. 123,216. (No model.)

To all whom it may concern:

Be it known that I, HENRY E. WEBER, a citizen of the United States, residing at Canton, in the county of Stark and State of Ohio, have invented a new and useful Improvement 5 in Dental Cuspidors, of which the following is a specification.

My invention relates to cuspidors usually made of glass or porcelain and attached or 10 supported on the side of a dental or other chair, and has for its object to so attach the cuspidor on its support that the bowl can be readily removed and replaced if broken or for 15 other purposes without disturbing or disarranging the other connections. I accomplish this object by the construction illustrated in the accompanying drawings, in which—

Figure 1 is a vertical section of a cuspidor and its support and attachment; and Fig. 2, 20 a perspective view of the support and attachment, showing parts broken away.

Similar numerals refer to similar parts throughout the drawings.

In the bracket 1, which is attached to a chair 25 or other object, (not shown,) is provided the supporting-collar 2, which may be formed integral with the bracket or connected with it, as illustrated. The upper part 3 of the supporting-collar is contracted in diameter, forming 30 the internal annular shoulder 3^a, and in the lower part is provided the internal screw-thread 4.

In the supporting-collar, immediately below the shoulder 3^a, is provided the elastic 35 ring 5, the normal internal diameter of which is as large as that of the contracted part of the supporting-collar above the shoulder, and the drain-pipe cup 6 is screwed into the lower part of the supporting-collar up against the 40 elastic ring, preferably with the intervening washer 7. The internal diameter of the washer and that part of the cup within the collar is as large as that of the contracted part of the collar.

45 The depending neck 8 of the cuspidor 9 is formed with its external diameter to neatly fit in the contracted part of the supporting-collar and is preferably provided with the annular shoulder 10 for resting on the upper 50 edge of the collar. The annular groove 11 is

provided in the cuspidor-neck, which groove is arranged to register with the elastic ring when the cuspidor is in place and is adapted to receive the expansion of the ring when the same is compressed by screwing the drain-pipe cup 55 against it. This groove may be rounded, as illustrated, or shaped in any other suitable manner to accomplish the purpose described.

When the cuspidor is put in place and the drain-pipe cup screwed up to compress the 60 elastic ring, the same is expanded inward to fill the annular groove on the neck of the cuspidor, and the cuspidor is thereby held firmly in place by an elastic connection which will not tend to crack or break it, and if it is desired to remove the cuspidor by reason of 65 breakage or otherwise the drain-pipe cup is turned out far enough to permit the elastic ring to resume its normal shape, when the cuspidor-neck can be lifted out of the supporting-collar without disturbing or disarranging 70 any other parts of the support.

What I claim as my invention, and desire to secure by Letters Patent, is—

1. The combination of a cuspidor, a neck 75 on said cuspidor, there being an external annular groove on said neck, a supporting-collar around said neck contracted to neatly fit the same above said groove thereby forming an annular shoulder, an elastic ring below 80 said shoulder normally passing said neck, and a drain-pipe cup screwed in said collar against said ring and adapted to compress the ring into said groove.

2. The combination of a cuspidor, a neck 85 on said cuspidor, there being an external annular groove on said neck and an external annular shoulder above said neck, a collar supporting said cuspidor-shoulder around said neck and contracted to neatly fit the neck 90 above said groove thereby forming an internal annular shoulder, an elastic ring below said collar-shoulder normally passing said neck, and a drain-pipe cup screwed in said collar against said ring and adapted to compress 95 the ring into said groove.

3. The combination of a cuspidor, a neck 100 on said cuspidor, there being an external annular groove on said neck, a supporting-collar around said neck contracted to neatly fit

the same above said groove thereby forming an annular shoulder, an elastic ring below said shoulder normally passing said neck, a washer below said ring, and a drain-pipe cup 5 screwed in said collar against said washer and adapted to compress the ring into said groove.

In testimony whereof I have signed my

name to this specification in the presence of two subscribing witnesses.

HENRY E. WEBER.
